UNITED STATES PATENT OFFICE.

ALBERT H. EHRLICH, OF ST. JOSEPH, MISSOURI.

REFRIGERATOR OR COLD-STORAGE ROOM.

Application filed January 30, 1922. Serial No. 532,796.

To all whom it may concern:

Be it known that I, ALBERT H. EHRLICH, a citizen of the United States, residing at St. Joseph, in the county of Buchanan and State of Missouri, have invented certain new and useful Improvements in Refrigerators or Cold-Storage Rooms, of which the following is a specification.

This invention relates to a refrigerator or cold storage room and has for its object to provide means for insuring a rapid and continuous circulation of air from the upper cooling compartment to the lower cooled compartment.

15 Figure 1 is a perspective view broken away to clearly illustrate the invention.

Fig. 2 is a transverse section through the upper part of the refrigerator.

Fig. 3 is a modified view showing a shield 20 over the central opening when it is desirable to use ice as a cooling medium.

The numerals 1 and 2 indicate the front and side walls respectively, the front wall being provided with a set of doors 3 for access to the lower provision compartment, the side walls being provided with windows 4. The bottom and roof or top wall 6 as well as the walls 1 and 2 being suitably insulated as illustrated.

30 The wall portions have secured thereto on the side directly above the doors supporting joists 7 adapted to support a cold storage pan arranged in the upper cooling compartment. This pan preferably consists of a plurality of joists 8—8 extending transversely of the refrigerator. Mounted upon these joists are baffle boards 9—9 suitably notched as at 10 to receive the joists 8 and these baffle boards are spaced from the outer walls of the refrigerator forming an air duct therebetween, suitably spaced braces 11—11 being arranged between the outer walls and the baffle boards. As disclosed in Fig. 2

40 joists 8 slant downwardly toward the center on their lower edges as at 12 being provided centrally thereof on the lower side with a recess 13. The numeral 14 indicates pans secured to the edges of joists 8 said pans being properly insulated to avoid condensation.

45 These pans are preferably spaced to form a central opening 15 which serves as a cold air duct to permit the cooled air to pass downwardly into the lower provision compartment and upwardly through the spaces 55 between the outer walls and the baffle boards as indicated in Fig. 1 by arrow. Gutters

16 are arranged along the inner edge of the pans to carry off any liquid that may be collected upon the pans.

Arranged within the chamber formed by the baffle boards are a plurality of brine tanks 17 being provided with suitable cooling coils 18. Spaced lugs 19 on top of the joists serve to insure proper spacing of the tanks to form an opening which registers with the opening 15 whereby the cooled air may pass downwardly therethrough. As disclosed in Fig. 3 the central opening 15 may be bridged over with a shield 20 to properly protect the opening 15 and prevent water getting down to the lower provision compartment in case ice is used as a cooling medium in place of cooling coils.

Owing to the size of this cooling pan, 75 the cooling compartment, or the several members making up this compartment, is preferably constructed in such a manner that the compartment may be shipped in a knock-down form thereafter being put together or 80 assembled in the refrigerator, it being understood that this form of cooling storage pan is made independently of any particular form of refrigerator and is adapted to be applied even to one in use.

85 It will thus be seen that I have constructed a cooling pan in such a manner that a circulation is maintained in the refrigerator of cooled air passing through the central opening and between the several tanks 90 striking the ice pans 14 rolling down between the center opening and passing into the cooling chamber below and finally passing upwardly through the annular opening around the edges of the cooling pan and up 95 into the upper compartment and again down through the central opening.

I claim:

1. A refrigerator comprising a building having walls, joists fastened to the walls, a plurality of secondary joists extending transversely of the building and supported by said first-mentioned joists, a plurality of baffle-boards having notches mounted between the secondary joists and embracing 100 said joists by means of the notches, said baffle-boards spaced from said walls to form a circulating air space, and a plurality of braces mounted on the ends of the secondary joists and extending between the walls of 105 said baffle-boards to support the baffle-boards and form a plurality of ducts for the 110

circulation of air, and pans supported at the lower edge of said secondary joists, said pans forming a division in the building between an upper cooling compartment and a

5 lower food compartment.

2. A refrigerator or cold storage room including a cooling compartment and a cold storage pan arranged therein, the cold storage pan made up of vertically disposed baffle-boards, approximately paralleling the walls of the refrigerator or cold storage room, transverse joists supporting the baffle-boards, braces extending vertically from the baffle-boards to the wall of the refrigerator or cold storage room and forming vertical air circulating flues through which the cold air from the cooling compartment below rises on its way to the top of the cold storage pan into which it descends finally

10 passing through the central opening, the lower edges of the joists sloping from opposite edges toward the center, pans secured beneath the sloping edges and gutters at the inner edges of the pans.

3. A refrigerator or cold storage room including a cooling compartment and a cold storage pan arranged therein, the cold storage pan made up of vertically disposed baffle-boards, approximately paralleling the walls of the refrigerator or cold storage room, transverse joists supporting the baffle-boards, braces extending vertically from the baffle-boards to the wall of the refrigerator or cold storage room and forming vertical air circulating flues through which the cold air from the cooling compartment below rises on its way to the top of the cold storage pan into which it descends finally

15 passing through the central opening, the lower edges of the joists sloping from opposite edges toward the center, pans secured beneath the sloping edges and gutters at the inner edges of the pans, and a shield supported upon the joists and bridging over the central opening.

20 In testimony whereof I affix my signature.

ALBERT H. EHRLICH.
